UNITED STATES PATENT OFFICE.

HUGO KARL SAKOWSKI, OF NEW YORK, N. Y.

PIN.

Application filed April 8, 1926, Serial No. 100,670, and in Germany May 19, 1925.

This invention relates to pins, and its object is to provide certain improvements of construction which impart to the pin the advantages both of an ordinary pin, such as smallness, lightness, cheapness and ready applicability for various purposes and of a so-called safety pin, such as reliability and absence of risk of accidents, so that my improved pin will be useful for domestic purposes as well as in the office, shop and factory line.

Ordinary straight and smooth pins in general use for joining together cloth, letters, documents and the like are objectionable since they frequently detach from the material and get lost and give rise to injuries.

My invention aims to remedy this defect, by constructing a one-piece pin comprising a head and a single shank, in such a manner that the frictional surface effect thereof will be greatly increased, and I attain this object by giving the shank a particular shape.

In the accompanying drawings forming a part of this specification I have shown, by way of exemplification, two embodiments of my invention.

In said drawings,

Figure 1 is an elevation of one form of the improved pin;

Fig. 2 is a section taken on the line II—II of Fig. 1;

Fig. 3 is a view similar to Fig. 1 but showing a modification;

Fig. 4 is a section taken on the line IV—IV of Fig. 3.

Referring to Fig. 1, the shank of the pin comprises three distinct portions or sections 4, 5 and 6. The upper or top section 4 is straight, and its outer end is shaped to form a head 3. The lower pointed section 6 is likewise straight. The short intermediate section 5 is coiled or twisted to form convolutions of decreasing diameter extending from the top section 4 to the point section 6, so that the contour or peripheral points of the convolutions of the shank lie in the surface of a cone, the base of which is near the top section 4 of the pin, as will be readily understood on an inspection of Fig. 1.

It will be seen that the wider convolutions near the top or head section 4 of the pin serve as a locking means to hold the pin firmly in the paper or cloth, the more so

since the upper portion of the intermediate section 5 comprising the said wider convolutions passes only for a short length through the pierced paper or cloth; while the lower portion of the said intermediate section 5, owing to its comprising the convolutions of a less diameter or to its reduced lateral extension, is adapted to pass easily, under pressure exercised on the head 3, through the paper or cloth for greater lengths. Thus the upper portion of the intermediate section 5 is mainly a locking means and the lower portion of the section 5 is mainly a guiding element.

Referring to the modification illustrated in Fig. 3, the shank of the pin likewise consists of three sections 4', 5' and 6'; and the end sections 4' and 6' are straight and relatively long, just as in the embodiment depicted in Fig. 1. But the short intermediate section 5' is not coiled or twisted, as will be clearly understood from Fig. 4. The section 5' is bent in a common plane over the whole of its length in a wave-like manner with the single bends or waves decreasing in width or height from the top section 4' towards the pointed section 6', so that the crests or ridges of the several waves will lie in the surface of a cone the base of which is near the head end of the pin, just as in the embodiment shown in Fig. 1. For this reason also the wider upper bends or waves near the top section 4' in Fig. 3 serve mainly as a locking means, while the smaller or narrower lower bends or waves near the point-end section 6' are chiefly a guiding element, as described hereinbefore with reference to Fig. 1.

Referring to Figs. 3 and 4, the numerals 8 and 9 indicate the extreme points of the crests of the waves contiguous to the head section of the shank; and as the right-hand portion 9 is a trifle longer than the left-hand portion 8, it is to be seen therefrom that the undulatory bend or height of the first wave is somewhat greater than, or in excess of, that of the second wave, and so on, and that the extreme points or crests of the several waves lie in the surface of a cone owing to the progressively and gradually decreasing height of the waves on both sides of the axis of the shank.

In accordance with the various purposes for which the pin may be used, it can be made as desired or required:

1. With a different number of convolu-

tions, waves or windings of the intermediate section 5 or 5' of the shank;

2. With convolutions, waves or windings having different forms, heights, depths, 5 diameters and lengths;

3. With shorter or longer straight top or head-end sections 4 or 4' as well as with shorter or longer straight lower or point-end sections 6 and 6';

10 4. And with a shank which is round, oval, flat, square or otherwise shaped in cross-section;

5. With a head having different forms, shapes and sizes.

15 6. In all cases, however, the convolutions, waves or windings decrease from the head-end section towards the point-end section, so that the peripheral or contour points, or the crests of the ridges of the waves, lie in the 20 surface of a cone.

The principal effects and advantages of the described pin are as follows:

25 The shank of the pin is formed to provide maximum frictional surface effect near the top or head-end section and minimum frictional surface effect near the point-end section.

30 When inserting the pin into a piece of material and consequently moving it in the direction of its point-end, the frictional surface effect it at first very slight and increases gradually towards the end of the operation, so that the pin readily advances into the 35 pierced material when a slight pressure is exerted on its head, and finally gets a firm hold in the material owing to the maximum locking or retaining effect of the deep windings near the head end of the pin.

40 When moving the pin from the material and consequently moving it in the direction of its head end, the maximum locking action of the deep windings near the head end

comes into full effect at the beginning of the operation, so that a certain pulling effort at the head end is required to remove the pin 45 from the material. The pin is thus prevented from becoming loose or detached accidentally.

In reducing my invention to practice, I find that the forms shown herein are the 50 most practical and preferred embodiments of which I am now aware; but realizing that certain conditions will necessarily vary in accordance with the particular use of the pin, I desire to emphasize the fact that 55 various minor changes in the construction and shape may be resorted to when required, without sacrificing any of the advantages of my invention and without departing from its scope as defined in the appended claims. 60

What I claim is:—

1. A one-piece pin, comprising a head, and a shank embodying a relatively-long, straight head-end section, a relatively-long, straight point-end section, and a relatively-short, intermediate section which is shaped 65 to form a longitudinal series of curved portions gradually decreasing in size from the head end towards the point end.

2. A one-piece pin, comprising a head, and a shank embodying a relatively-long, straight head-end section, a relatively-long, straight point-end section, and a relatively-short, intermediate section which is shaped 75 to form a longitudinal series of curved portions gradually decreasing in size from the head end towards the point end; said curved portions extending over the whole length of said intermediate section so that their contour or peripheral points lie in the surface 80 of a cone the base of which is near the head end of the pin.

In testimony whereof I affix my signature.

HUGO KARL SAKOWSKI.
